UNITED STATES PATENT OFFICE.

HENRY LIGHTBOURNE, OF DETROIT, MICHIGAN.

DESIGN FOR A TIRE-PROTECTOR.

53,421.

Specification for Design.

Patented June 10, 1919.

Application filed January 10, 1919. Serial No. 270,595. Term of patent 14 years.

To all whom it may concern:

Be it known that I, HENRY LIGHTBOURNE, a subject of the King of Great Britain, residing at Detroit, in the county of Wayne and State of Michigan, have invented a new, original, and ornamental Design for a Tire-Protector, of which the following is a specification, reference being had to the accompanying drawing, forming part thereof.

Figure 1 is a perspective view of the tire protector, and

Copies of this patent may be obtained for five cents each, by addressing the "Commissioner of Patents, Washington, D. C."

Fig. 2 is a side elevation of protectors as applied to a tire.

I claim:

The ornamental design for a tire protector, as shown.

HENRY LIGHTBOURNE.
